UNITED STATES PATENT OFFICE.

MATT BURKE, OF DULUTH, MINNESOTA.

VESSEL-RAISING APPARATUS.

1,329,225.

Specification of Letters Patent. Patented Jan. 27, 1920.

Application filed September 22, 1919. Serial No. 325,398.

To all whom it may concern:

Be it known that I, MATT BURKE, a citizen of the United States, residing at Duluth, in the county of St. Louis and State of Minnesota, have invented new and useful Improvements in Vessel-Raising Apparatus, of which the following is a specification.

This invention relates to an improvement in means for raising sunken vessels, and generally stated embodies an independent means by which the sunken vessel may be directly located, and means operated wholly from the surface of the water for attaching lifting cables to said sunken vessels, and means for operating the sunken cables to raise the vessel to the surface.

In the directing means the invention comprises a body constructed for travel below the surface of the water and carries a powerful light, the rays of which are bent downwardly so that an observer traveling directly above the submersed detector can readily locate the sunken vessel. The cable attaching means comprehends a boring tool adapted to be operated from the surface of the water and in the use of which an opening is formed in the sunken vessel and the cable following the boring tool through such opening is automatically connected to the sunken vessel to prevent separation therefrom. The invention also comprehends a surface vessel equipped with cable lifting means so that the cables, a number of which have been attached as described, to the sunken vessel, may be drawn upon to raise the vessel to the surface.

In the drawings:

Figure 1 is a view in elevation showing the improved detector in use.

40 Fig. 2 is an enlarged bottom plan of the detector.

Fig. 3 is a front elevation of the same.

Fig. 4 is a view in elevation of the lower end of the cable lifting means.

45 Fig. 5 is a vertical central sectional view of the same.

Fig. 6 is a section on line 6—6 of Fig. 5.

Fig. 7 is a section on line 7—7 of Fig. 5.

Fig. 8 is a view in elevation illustrating 50 the action of the cable securing means following the passage of the boring means through the opening in the deck of the sunken vessel.

Fig. 9 is a view in elevation of the upper 55 portion of the cable attaching means,

Fig. 10 is a section on line 10—10 of Fig. 9.

Fig. 11 is a view in elevation of the drill machine by which the cable attaching means is operated.

60 Fig. 12 is a view in elevation of the surface vessel for supporting the cable attaching and cable lifting machinery.

Fig. 13 is a plan of the same.

Fig. 14 is a longitudinal section of the 65 same.

Fig. 15 is an enlarged view in elevation of the cable-lifting machinery; one side being removed to clearly illustrate the same.

As previously stated, the present invention involves three distinct types of apparatus, one a detector in the use of which the location of the sunken vessel may be readily ascertained, second a cable attaching means by which suitable lifting cables may be attached to the sunken vessels, and third a cable lifting means, by which the cables so attached to the vessel may be drawn upon to raise the vessel to the surface. The following specification will deal with these independent parts separately.

Vessel detector.

The improved detector comprises a hollow body 1 substantially of cigar shape, 85 within which at the forward end is located a powerful light 2. The light 2 is preferably an electric light, fed from a suitable source on the surface of the water, and in rear of this light is arranged a deflector, as 90 at 3, so that the light rays are directed downwardly. The body 1 is provided with a heavy steel weight, pendent thereof through rods 5, so that the body will remain in an upright position, and will sink to a considerable depth. The top surface of the body has a guiding vane 6 whereby the body is kept straight in the towing operation, and the sides of the body are provided with directing vanes 7, which incline downwardly 95 and forwardly, overcoming the tendency of the body to rise, and compelling it to travel over a substantially straight line.

In use, the detector is towed as by a tow line 8 from a motor or other boat 9, and the 105 wire serving the light 2 may be fed from a suitable source on this boat. The power boat 9 also tows, as by two lines 10, an observer's boat 11, and the relative length of the tow lines 8 and 10 are such that the ob- 110

server's boat is directly above the detector 1. By this means the observer in the boat 11 is enabled to detect the exact location of the sunken vessel in order that the subsequent 5 operation may be carried out.

Cable attaching means.

The cable attaching means embodies a hollow casing made up of sections 12, within 10 flanges 13 provided with clamping means 14 whereby the sections may be secured in endwise relation to provide an elongated casing of the desired length. Rotatably mounted within the casing 12 is a driving tube made 15 up of sections 15, these sections at their meeting ends being formed with coöperating projections and notches 16 whereby when assembled in endwise relation, they may interlock to secure simultaneous rotation. A 20 cable 17, as a wire rope of appropriate thickness, is adapted to pass lengthwise, and within the operating tube 15, the lower end of the cable having fixedly secured thereto a solid section 18, the upper end of 25 which is formed with notches 19 to coöperate with the projections 16 on the lowermost section 15 of the operator's tube. The lower end of the member 18, which is in effect a drill head, is formed with a drill point 30 20 this point being of step formation as indicated at 21, whereby the drill point proper may be caused to take hold even if the drill is operating against a relatively inclined surface. At diametrically opposite points the 35 drill head 18 is longitudinally slotted, as at 22, and arms 23 are adapted to seat in said slot and when seated lie flush with the surface of the drill head. A spring 24 is mounted in the drill head between arms 23, said 40 spring acting when the arms are free to project said arms into a relatively horizontal position, that is diametrically of the drill head 18, to form projections beyond said drill head, as clearly shown in Fig. 8.

45 The lowermost section of the casing 12 is formed at its free end with a circular or spherical bearing 25 and a bearing plate 26, preferably formed in two sections, is centrally formed with an opening 27 to coöperate with the spherical bearings 25. The lower surface of the bearing plate 26 is formed with sharp points 28, and this bearing plate functions to engage the surface of the vessel against which the boring tool is 50 55 to be operated, and to hold a connection substantially firm for the operation of the drill. The cable 17 immediately beyond the free end of the uppermost section 15 of the boring tube is provided with a clamp 29 whereby the cable is held tight within said 60 65 boring tube, in order that the connection of the lowermost section of said boring tube and the drill head may be maintained during the boring operation.

65 The uppermost or final section 15 of the

boring tube is formed with a longitudinal keyway 30, and a driving gear 31 having an appropriate key is adapted to slidably co-operate with this section. This gear 31 forms part of a drill machine 32, including 70 an appropriate frame work 33, and suitable driving mechanism 34, including a motor 35, whereby the gear 31 may be operated. The lower portion of the frame 33 of the drill machine carries spaced clamping members 75 36 within which is clamped the uppermost section of the casing 12. The casing is thus held fixed with relation to the machine while the boring tube together with the drill head attached thereto is rotated in order that the 80 boring tool may form an opening in the shell of the vessel with which it is engaged. A feeding machine 37 is adapted to be clamped to the boring tube below the gear 31 and a hand feeding device 38, of appropriate type, is mounted upon the frame 33, whereby the boring tube cable and drill may be bent downwardly as desired. Of course it is apparent that the weight of these parts is practically sufficient for feeding purposes, 85 but the hand feed mechanism is here shown in the event that the material encountered will require the addition of such mechanism in order that the drill may be properly fed therethrough.

95 With the use of the improved cable attaching means, it is apparent that the drill will force its way through the shell of the sunken vessel and that following the drill head through such opening, such head upon release of the cable clamp 29 may be separated from the boring tube and the latter together with the casing 12 raised to the surface. As the drill head passes through the opening, the arms 23 are spread below 100 105 the shell of the vessel, indicated at 39 in Fig. 8, thus securing the cable to the vessel.

Cable raising means.

In Figs. 12, 13 and 14, there is shown a 110 surface vessel which is designed to support the cable attaching mechanism just described and also the cable raising means. This vessel which is here shown as substantially of scow form comprises a hollow 115 body 40 formed with a central well 41 opening wholly through the vessel from top to bottom but within the side limit thereof. A suitable deck support 41 is secured upon this vessel, and housings may be provided 120 on this deck for the reception of cable attaching machinery and the cable raising means. A hoisting means, such as a drum 42 is mounted on the deck 41, and driven through suitable worm gearing 43 operated 125 by a motor 44. Following the attachment of the cable to the sunken vessel, as described, which cable in the operation described, passes through the support 41, the upper end of said cable is secured to the 130

drum 42, and the hoisting machinery will draw upon said cable with the effect to raise the sunken vessel to the surface.

It is of course to be understood that a number of vessels 40 are to be employed, as it is apparent that a number of cables must be attached to the vessel and to different points thereof in order that the same may be raised without imparting strain on the cable. Of course as many cables as may be necessary are contemplated for use, in which event the vessel for each such cable will be employed.

Having described the invention what is claimed as new is:—

1. A cable attaching means for raising the sunken vessel, including a rotating boring tube, a drill removably connected thereto, and a cable secured to the drill head and extending longitudinally of the tube.

2. A vessel raising means including an operating tube, a drill head removably connected thereto, a cable secured to the drill head and passing longitudinally through the tube, a casing within which said tube is operated and means on the drill head to automatically project beyond the same when the drill head has been lowered beyond the casing.

3. A cable attaching means for raising sunken vessels including a casing, a tube rotatable therein, a drill head removably connected with the lower end of the tube, a cable secured to the drill head and passing longitudinally through the tube, arms carried by the drill head and adapted to be projected beyond the surface of the drill head, when the latter has been lowered below the casing and means for rotating the tube.

4. A cable attaching means for raising sunken vessels, including a casing, a supporting tube carried thereby, an operating

tube mounted within the casing, a drill head removably connected to the lower end 45 of the tube, a cable secured to the drill head and extending longitudinally of the tube, and means for clamping the upper end of the cable with relation to the tube to maintain the drill head and tube in connection, 50 an arm carried by the drill head and held in operative relation within the casing, said arm being projected to lateral position when the drill extends below the casing.

5. A cable attaching means for raising 55 vessels, comprising a casing made up of endwise connected sections, a tube rotatable within the casing and made up of endwise connections, a drill head adapted for removable connection with the lower end of 60 the tube, a cable secured to said drill head and extending longitudinally of and within the tube, arms carried by the drill head and held in inoperative relation to said head and while the head is within the casing, 65 and means for projecting said arms laterally of the drill head when the latter has moved below the casing.

6. A cable attaching means for raising 70 vessels, comprising a casing made up of endwise connected sections, a tube rotatable within the casing and made up of endwise connections, a drill head adapted for removable connection with the lower end of the tube, a cable secured to said drill head and 75 extending longitudinally of and within the tube, arms carried by the drill head and held in inoperative relation to said head and while the head is within the casing, and means for projecting said arms laterally of 80 the drill head when the latter has moved to below the casing and a clamp for clamping the casing and means carried by the casing for rotating the tube.

In testimony whereof I affix my signature. 85
MATT BURKE.
